GUIDING DEVICE FOR LONG DRAFT APRONS

James L. Truslow, Whitinsville, Mass., assignor to Whitin Machine Works, Whitinsville, Mass., a corporation of Massachusetts

Application July 17, 1933, Serial No. 680,692

21 Claims. (Cl. 19—131)

This invention relates to long draft spinning mechanism in which endless belts or aprons are used as part of the drafting system and its objects are to improve the devices, or cradles, used for supporting and guiding the aprons. The more specific objects are to insure that the aprons will be properly set up in the machine and reliably retained in correct position; to insure that they will be properly guided therein so as to minimize edge wear; to prevent the removal of the cradle and top roll together; to facilitate the use generally of these devices and particularly the operation of repairing broken ends; and to accomplish these objects without the addition of separable parts likely to fall into the machine.

A preferred form of the invention is shown in the drawings, in which

Fig. 1 is a sectional side elevation of portions of a long draft spinning mechanism embodying my improvements, taken along the line 1—1 in Fig. 2;

Fig. 2 is a plan view looking in the direction of the arrow 2 in Fig. 1;

Fig. 3 is a plan view of the guiding device;

Fig. 4 is a side elevation thereof with the guide clips in open position;

Fig. 5 is a plan view of the blank from which the guide frame is constructed;

Fig. 6 is a side view of one of the guide clips, and

Fig. 7 is a perspective view of one of the belt guiding studs.

Referring to Figs. 1 and 2, I have shown a roll stand 19 supporting back rolls 11 and 12, intermediate rolls 13 and 14 and front rolls 15 and 16. The lower rolls 11, 13 and 15 are mounted in bearings supported on the roll stands 10 and these rolls are positively driven in predetermined speed relation. The upper rolls 12, 14 and 16 rest on the lower rolls 11, 13 and 15 and are held in position by bearing members 18, 19 and 20.

The members 20 are mounted on a cross rod 21 (Fig. 1) and the members 18 and 19 are mounted on rods 22 secured in the ends of the members 20. The spacing of the intermediate and front lower rolls 13 and 15 may be varied by loosening binding screws 10^a and the upper rolls may be spaced to correspond by adjusting the blocks 18 and 19 on the rods 22.

Each yarn Y passes through a guide-eye 23 by which it is directed between the back rolls 11 and 12. The yarn then passes between aprons 25 and 26 on the intermediate rolls 13 and 14 and is delivered by the aprons to the front rolls 15 and 16, which are rotated at substantially

higher speed than the rolls 13 and 14 to provide the desired draft. Any desired provision may be made for weighting the upper rolls.

The parts thus far described are of the usual form and in themselves constitute no part of my present invention, which relates particularly to devices for supporting and guiding the aprons 25 and 26.

For this purpose I provide removable guide frames 30 each preferably formed from the blank 10 shown in Fig. 5. The frame comprises side plates 31 joined by a roving deflecting table 32, preferably integral with the side plates, and by a cross rod 33 fixed in the side plates and holding them in spaced relation.

Studs 35 are secured in holes 36 in the side plates 31 and constitute front guides for the aprons 25 and 26, the function of the studs 35 being clearly shown in Fig. 1. Such studs form no part of the present invention being the subject of a companion case.

The side plates 31 are provided with upwardly concave recesses or bottom notches 40 and with downwardly concave recesses or top notches 41, separated by narrow connecting portions 42. The portions 42 extend between reduced portions of the rolls 13 and 14 when the guiding devices are in place.

The side plates 31 are inwardly offset as indicated at 44 and the rear portions 45 of the side plates 31 constitute guides to limit the traverse of the yarn and to prevent the yarn from running off the edges of the aprons 25 and 26.

Guard members 50 (Figs. 4 and 6) are pivoted on studs 51 secured in openings 52 (Fig. 5) in the side plates 31. Each guard member 50 comprises a hook-shaped portion 53 (Fig. 6) adapted to extend around the under side of the lower roll 13 and to form a guide for the edges of each lower apron 25 as the apron crosses the wide lower open ends of the recesses 40 in the side plates 31.

The upper portion 54 of each guard 50 extends above the upper run of the upper apron 26, and a projection 55 of the guard extends between the guide studs 35 when the clip is in operative position. These upper portions furnish guiding surfaces for the various runs of the aprons, and the edge 56 (Fig. 6) of the guard 50 is normally engaged by a portion of the upper roll 14 as shown 50 in Fig. 1, thus preventing release of the guard as long as the roll 14 is in operative position.

When the guards 50 are moved to the position shown in Fig. 4, the entire guiding device including the guards 50 may be readily removed 55

from the lower drawing roll 13, but when the guards are in the raised or closed position shown in Fig. 1, the guiding device is securely mounted on the rolls 13 and 14 and is firmly held from displacement relative thereto.

The guards are raised to the position in which they do not obstruct the top notches by the engagement therewith of the bottom roll when the latter is entered into the bottom notches of the frame. This insures that the top notches are open when the cradle has been fully seated on the bottom roll and also that the guards are in proper apron-guiding positions when the top roll is replaced.

It will be noted that the guards 50 thus have several functions; one is to guide the apron to keep it from overlapping the shoulders or ends of the roll, which injures it, or from scraping or wearing on the edges of the notches; another is to lock the cradle to the bottom roll; and another is to form an interlock with the top roll either for the purpose of insuring against a misplaced cradle or an improperly guided apron, or both as the case may be. These functions are obviously not interdependent since it will be apparent that a single guard member serving merely as a latch or lock will suffice to lock the cradle to the bottom roll or to interlock it with the top roll, whereas two guard members serving merely as apron guides are required, one on each side of the apron, for keeping it from running over the roll shoulders.

The table 32 functions by catching the advancing and drooping end of the roving when the machine is being creelied up, or a broken end repaired, and by deflecting it into contact with the upwardly moving surface of the bottom apron which then picks it up and carries it through. To perform this function the deflector table is located behind the bottom draft roll and below the path of the roving, and in this position it serves also as one of the cross-members of the cradle frame.

Having thus described my invention and the advantages thereof, I do not wish to be limited to the details herein disclosed, otherwise than as set forth in the claims, but what I claim is:

1. A cradle for long-draft spinning aprons comprising an apron-guiding frame shaped to receive top and bottom draft rolls and including a roving-deflecting table located below the path of the roving and close to the back side of said bottom draft roll, whereby a roving end may fall thereon and be lifted therefrom to its normal path by said bottom roll.

2. A cradle for long-draft spinning aprons comprising two side plates having top and bottom draft roll notches and united by an integral cross member in the form of a roving-deflecting table located horizontally in rear of the bottom roll and below the normal path of the roving.

3. In combination with drafting rolls, a cradle for long-draft spinning aprons comprising side plates held together by cross-members and formed with notches to receive the bottom intermediate roll, an endless apron on said bottom roll, said side plates being inwardly offset in rear of said bottom roll and apron and one of said cross-members being in the form of a deflecting table connecting the offset parts of the side plates and located in position to receive a roving end drooping from the lower back roll and steer it into contact with said apron.

4. In long-draft spinning, the combination of the back and intermediate rolls, aprons on the

intermediate rolls, a cradle formed of side plates notched to receive the intermediate rolls, said cradle including a deflecting table directly behind the lower apron and vertically below the roving delivery of said back rolls, where a roving end from said back rolls will encounter it and be deflected thereby into contact with said lower apron.

5. In long draft spinning apparatus, top and bottom endless draft aprons, a pair of back rolls 10 feeding roving to said aprons, and a roving-deflecting table located beneath the delivery side of the back rolls in position to receive a broken end emerging or drooping therefrom and guide it into contact with the bottom apron. 15

6. In combination with the structure of the preceding claim 5, a removable cradle for guiding the endless aprons, and said roving-deflecting table being carried on said cradle.

7. In combination with the structure of claim 20 5, a removable cradle for guiding the endless aprons composed of a frame with side plates, and said roving-deflecting table forming one of the cross-connecting members of said frame and being integral therewith. 25

8. A cradle for long-draft spinning aprons comprising a frame shaped to receive the top and bottom draft rolls, and a movable latch member permanently attached to said frame and movable thereon to lock the frame to the bottom 30 roll.

9. A cradle for long-draft spinning aprons comprising a frame having top and bottom notches for the draft rolls, a guard member movably mounted thereon adapted to obstruct 35 entrance of the top roll into the top notch, such member having a part engaged by the roll in the bottom notch and moved thereby to non-obstructing position with reference to the top notch.

10. A cradle for long-draft spinning aprons 40 comprising a frame having a space to receive the top roll, latch means movable to lock the frame to the bottom roll, said latch means obstructing said top roll space when moved to its unlocking position. 45

11. A cradle for long-draft spinning aprons comprising a frame having top and bottom roll notches and a member thereon movable into obstructing position alternately with respect to a top notch and a bottom notch. 50

12. A cradle for long-draft spinning aprons comprising a frame shaped to receive the top and bottom draft rolls and an interlocking latch means co-acting with both rolls and movably mounted on said frame.

13. A cradle for long-draft aprons comprising side plates, means to hold said plates in fixed spaced relation, said side plates having bottom notches to accommodate the lower intermediate roll, and guards pivotally mounted on said side plates and substantially closing the lower portions of said recesses when in operative position, said guards being held in operative position by engagement of a portion of each guard with the upper intermediate roll. 60

14. A cradle for long-draft aprons comprising side plates, means to hold said plates in fixed spaced relation, said side plates having bottom notches to accommodate the lower intermediate roll, and guards pivotally mounted on said side plates and substantially closing the lower portions of said notches when in operative position, said guards having upwardly extending portions engaging the upper intermediate roll to prevent 70 75

opening movement of said guards and also providing extended belt-guiding surfaces.

5. A cradle for long-draft spinning aprons comprising a frame composed of united side plates having bottom notches to receive the bottom draft roll, a guard member permanently and pivotally attached to said frame, its range of pivotal movement serving to bring it into and out of closing relation to said bottom notch, and
10 means for retaining said member in closed position accessible on the upper part of said frame.

15. A cradle for long-draft spinning aprons comprising a frame composed of united side plates with bottom notches for receiving the bottom draft roll, a guard member for substantially closing said notch, said member being permanently pivotally attached to said frame to swing upwardly toward and downwardly from said bottom notch and means, independent of its pivotal
20 attachment, for retaining said member in its upper position.

25. A cradle for long-draft spinning aprons comprising a frame having top and bottom notches respectively for receiving top and bottom draft rolls and composed of side plates and cross members holding said plates in predetermined relation, one of said cross members being forward and another in rear of said bottom roll notches, and a guard pivotally attached to one of said side plates and adapted to swing up and down in the space between said two cross members and substantially closing said notch in its upper position.

30. A cradle for long-draft spinning aprons comprising a frame composed of side plates
35

formed with notches to receive the top and bottom rolls, each plate having a flat latch permanently pivoted to and against its inner face, the pivotal point being forward of the bottom notch and the lower extremity of said latch serving to close the entrance to the bottom notch, and said latches being independent of each other on opposite sides of the apron on said bottom roll and accessible from the top of the frame.
5

19. In long-draft spinning, the combination 10 with top and bottom rolls, aprons thereon, a cradle for the aprons comprising side plates notched to receive the bottom roll and provided with forward bearings for the top and bottom aprons, and edge-guiding means for the aprons 15 extending across said notches and above and below said apron bearings.

20. A cradle for long draft spinning aprons comprising a frame shaped to receive top and bottom draft rolls, a movable latch member permanently attached to said frame and movable thereon to lock the frame in position, said member having an upwardly extending part accessible from the upper side of the frame.

25. A cradle for long draft spinning aprons comprising a frame having notches formed therein to receive a draft roll and having movable apron edge-guiding means, said means being pivotally mounted to hold two positions, in one of which a portion of said means intrudes on 30 the roll space in said notches and said means being movable to its other, working, position by engagement with a roll entering said notches.

JAMES L. TRUSLOW. 35
